UNITED STATES PATENT OFFICE

RAY T. DE VOE, OF FLINT, MICHIGAN, ASSIGNOR TO MARVEL CARBURETOR COMPANY,
A CORPORATION OF MICHIGAN

STRAINER AND METHOD OF ASSEMBLING SAME

Application filed October 8, 1928. Serial No. 310,980.

This invention relates to a screen attachment for the fuel inlet connection to carburetors.

As is well known, the fuel supplied to carburetors is frequently dirty, carrying water, scale and dust particles in its normal state, such foreign matter being apt to clog up the fine orifices necessary in carburetor metering nozzles, as well as affecting the seating of the

10 float operated valve, with a possibility of flooding the carburetor. It is therefore an object of this invention to provide an easily and economically manufactured screen assembly for the fuel supply to the carburetor

15 float chamber that can be repeatedly removed for cleaning and afterwards replaced without danger of damaging the screen or of misplacing the same and thus rendering the screen inoperative.

20 It is also an object of this invention to provide an improved screen assembly for the purpose described that incorporates a water and sediment trap apart from the screen, so that the effective area thereof will not be impaired by the heavier particles of sediment that are first to settle out upon a decrease in the velocity of fuel flow due to the sudden enlargement of the fuel passage at the chamber surrounding the screen.

25 30 It is another object of this invention to provide an improved screen mounting including a permanent mounting of one end thereof in one member and a pilot member for the other end of the screen.

35 Other and further important objects of this invention will be apparent from the disclosures in the specification and the accompanying drawings.

40 This invention (in a preferred form) is illustrated in the drawings and hereinafter more fully described.

On the drawings:

45 Figure 1 is an elevation, partly in section, of a carburetor float chamber having a device embodying the features of this invention attached thereto.

Figure 2 is an enlarged section on the line II—II of Figure 1.

50 Figure 3 is an enlarged fragmentary section similar to Figure 1.

As shown on the drawings:

The carburetor float chamber structure comprises a bowl 10 having a float 11 therein to actuate a needle valve 12 which seats in a vertically passaged plug 13 screwed into the chamber side of a depending boss 14 on the bowl bottom. The passage in the plug 13 opens into a central passage 15 in the boss, which passage extends through a depending pilot boss 16 adapted to engage within the upper end of a cylindrical fine meshed screen 17.

The boss 15 is formed with a depending cylindrical shell 18 spaced from the pilot 16 and having a series of perforations 19 therein, the lower end of the shell 18 being threaded to receive a closure plug 20. The closure plug is centrally recessed at 21 and has an initially vertical annular groove 22 formed in the bottom of the recess, with an inner cylindrical flange 23 projecting upwardly from the bottom of the recess. After the lower end of the screen 17 has been inserted in the groove 22, the upper edge of the flange 23 is expanded or spun over into the position shown in Figure 3 to slightly distort the lower portion of the screen and pinch the distorted portion against the wall of the recess 21. This structure forms a permanent attachment between the screen and the plug so that when the plug is unscrewed from the shell 18 the screen is withdrawn from the pilot boss 16 and forms in effect an integral part of the plug.

An annular member 24 envelops the shell 18 and is formed with a chamber 25 extending below the perforated portion of the shell to form a sediment trap. The member 24 is rotatable about the shell in order to adjust the position of a fuel inlet boss 26 to suit any installation, the upper edge of the member 24 bearing against a gasket 27 seating on a shoulder on the boss 14. The plug 20 is formed with a radial flange 28 which is provided to compress a second similar gasket against the lower edge of the member 24 thus sealing the same against leakage when the plug is drawn up tight after turning the fuel inlet boss 26 into the desired position.

The operation of the device is as follows:

Fuel enters through the boss 26 and spreads around the shell 18 in the chamber 25, losing considerable velocity due to the relatively large size of the chamber, with a consequent deposition of the heavier foreign matter in the lower part of the chamber. From the chamber fuel flows through the perforated shell 18 and then through the screen 17 and up to the float valve.

To clean the strainer, the plug 20 can be unscrewed, carrying with it the screen 17, and the member 24 can then be slipped off the shell 18 to clean out the chamber 25. In reassembling the device the member 24 is first placed in position and the plug inserted, the upper end of the screen enveloping the pilot boss 16, the edge of which is rounded to permit easy engagement of the somewhat flexible screen cylinder.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

A fuel strainer for a carburetor having a float-housing body, a depending perforated shell on the body, means cooperating with the shell to define an annular fuel directing chamber and a sediment pocket, the said means comprising an enveloping member for the shell partially spaced therefrom and having a fuel entrance passage to the annular chamber so formed, means cooperating with the shell to define another annular chamber, said means comprising a sealing plug in threaded engagement with the shell, a cylindrical screen member mounted on the plug, and a passaged depending boss on the body entered in the screen member.

In testimony whereof I have hereunto subscribed my name at Flint, Genesee County, Michigan.

RAY T. DE VOE.
